UNITED STATES PATENT OFFICE

FORREST E. HOLLADAY, OF SALEM, OREGON

TAPE COATING AND AFFIXING DEVICE

Application filed December 15, 1930. Serial No. 502,513.

My present invention relates to improvements in tape coating and affixing devices of the hand manipulated type, and adapted to coat a tape with gum, mucilage, or other similar adhesive, and simultaneously affix the coated tape to a desired surface.

While the implement of my invention is adapted for various purposes and uses, it is particularly designed for employment in 10 coating and affixing printed telegraphic records or messages upon the blank sheet, to form the usual telegram. Thus the printed tape or paper strip, after it has received its record, is passed through the implement of 15 my invention, and during its passage through the implement the liquid adhesive is applied to the rear or blank face of the tape, and as the tape emerges from the implement, the tape is affixed to the blank sheet provided 20 therefor. The blank sheet is usually a sheet of paper, and the record tape is affixed to the sheet of paper in parallel lines with the printed side of the paper strip or tape up, and the coated side firmly affixed to the 25 paper sheet.

In carrying out my invention I provide a device or hand operated implement equipped with a pressure roller by means of which the coated tape or paper strip is 30 rolled and affixed on the sheet as the strip emerges from the implement, and in the affixing of the strip this operation is accomplished without necessity for handling the coated strip, thus avoiding soiling of the 35 fingers as well as soiling of the paper sheet, and insuring a clean and neatly finished telegram.

The device is simple in construction, composed of a minimum number of parts compactly associated and readily separated for 40 cleansing, repairs, or adjustment, and facile in operation for the performance of its functions.

The invention consists in certain novel 45 combinations and arrangements of parts as will hereafter be more fully set forth and claimed. In the accompanying drawings I have illustrated one complete example of the physical embodiment of my invention 50 wherein the parts are combined and arranged

according to the best mode I have thus far devised for the practical application of the principles of my invention. It will be understood that the parts may be fashioned from suitable materials, in various sizes and shapes for adapting the implement to a variety of uses. 55

Figure 1 is a view in side elevation of the coating and affixing device of my invention, showing by dotted lines the paper strip as it 60 is passed through the device and affixed to the surface of a sheet or other object.

Figure 2 is a front end view of the device of Figure 1.

Figure 3 is a face view showing the hinged cap opened from its head to disclose the guide means for the strip as it passes transversely 65 through the device.

Figure 4 is a longitudinal sectional view 70 of the device.

Figure 5 is an enlarged detail sectional view of the cap and head.

Figure 6 is a sectional detail view at line 6—6 of Figure 5.

Figures 7 and 8 are perspective views of 75 the pressure plate and resilient pressure blade therefor.

Figure 9 is an enlarged detail view of part of the cap of Figure 3.

In the preferred form of my invention I 80 employ a receptacle 1 of suitable size, and preferably cylindrical in shape, as a reservoir for containing the liquid glue, gum, mucilage, paste or other adhesive to be applied to the tape T. The open end of the receptacle is provided with external threads, and a cap 2 having a flanged portion 3 is threaded on the receptacle, to close the open 85 end after the receptacle has been filled to a suitable capacity with the liquid adhesive. 90

The cap 2 is provided with an elongated, rectangular slot or hole 4 for the outlet of the liquid adhesive, and the lower wall of this slot is fashioned with a serrated knife edge 95 5 to "wipe" the paper strip of excess coating as the strip passes down in front of the outlet slot. The serrations or teeth in the knife edge tend to form miniature, parallel ridges of adhesive, extending longitudinally of the strip, which ridges are of course displaced 100

or flattened as the strip or tape is "laid" or adhered to the blank or other object to which the tape is to be applied. The coated tape passes the serrated knife edge in frictional contact therewith and excess material is wiped from the tape while at the same time an ample quantity of the adhesive remains on the tape for efficient operation of the device.

10 Across the outer face of the cap is arranged a transversely extending, integral, tongue 6, and the slot 4 opens through this tongue. This tongue is the same width as the tape T and the knife edge 5 is flush with the outer

15 face of the tongue. Below the knife edge a groove 7 is formed in the face of the tongue and this groove forms a recess at the coated side of the tape in order that the coated side of the tape may pass from the device without

20 contacting with any surface that would otherwise disturb the coating of adhesive. It will of course be understood that the side of the tape toward the interior of the receptacle is coated as it passes the adhesive in the slot 4.

25 On the top of the cap are provided two spaced pins 8 to enter complementary perforations or holes in the bottom of a channel guide 9, in which guide the tape is laid as it comes from the roll, and the tape is guided

30 between the two inwardly converging walls 10 of the channel guide. At its front end, the channel guide is fashioned with a rounded face 11 over which the tape passes smoothly, and by which the tape is guided to the face

35 of the tongue 6. The channel guide is detachably mounted on the cap by means of the pins and the holes in the guide, and the latter is clamped to the receptacle by means of two pairs of spring arms 12, 12 that clasp or clamp themselves about the receptacle.

40 At one side of the cap a head 13 is hinged as indicated at 14, and this head is circular in shape and of approximately the same diameter as the cap. The head is adapted to

45 swing to closed position over the face of the cap, and a spring blade 15, seated in grooves 16 in the sides of the head and cap and secured to the head by a screw, is designed to snap over the edge of the flange 3 of the cap and fasten the head against the face of the tongued cap.

50 Within the head is mounted a pressure plate 17 for the tape T, and this plate, which is the same width as the tongue 6, is fashioned at its opposite ends with hooks 18. The pressure plate and the face of the tongue 6 form a passage between them through which the tape passes as it is being coated and guided through the device.

55 A pressure blade 19, of resilient material, is fashioned with angular flanges 20 at its ends which flanges bear against the back face of the pressure plate, and an adjusting screw 21 is threaded in the head to provide pressure against the blade and plate. The pres-

sure plate and the pressure blade are located in a slot 22 in the inner face of the head, which slot is complementary to the tongue 6, and the slot or groove is of a size and shape to receive the tongue.

70 The groove is countersunk as at 22' and near the opposite ends of the groove are fashioned a pair of oppositely extending hooks 23, integral with the head and forming the top and bottom walls of the countersunk part 22' of the groove. The hooks 18 of the pressure plate are snapped over these stationary hooks 23, and the pressure plate encloses the pressure blade within this countersunk recess 22'. By turning the screw 21 it will be apparent that the pressure or tension of the resilient pressure blade against the pressure plate may be varied to vary the space between the pressure plate and the tongue and adjust these guiding elements to the tape passing between them. The side walls of the groove 22 guide the edges of the tape, and the pressure plate holds the tape against the tongue, as well as against the serrated knife edge or scraper 5, to prevent escape of the adhesive and also to prevent application of an excess coating to the tape.

75 The resilient blade is confined in the countersunk recess of the head by the spaced hooks 23, 23, and pressure of the screw on the blade holds the flanges of the blade against the pressure plate with sufficient force to prevent loosening of the parts. For purposes of illustration the parts are exaggerated in Figure 5, and the tape is indicated by a dotted line passing through the groove 22 between the tongue and the pressure plate. It will be understood that the tape, as it passes through the coating device, is held with sufficient friction to prevent buckling of the tape and to prevent leakage of the liquid adhesive, the friction being adjusted or varied by manipulation of the screw 21.

80 After the tape emerges from the coating device, it is led under a pressure roller 24, as indicated in Figure 1, and the coated tape is laid or affixed by the roller on the surface provided for that purpose.

85 The presser roller is journaled in the forked arm 25 that is provided with two spaced guide fingers 26, between which fingers the tape is guided to the roller, before it passes under the roller. The forked arm is fashioned integral with an attaching plate 27, which is secured by screws 28 to the outer face of the head 13, and this attaching plate is provided with a hole 29 to permit ready access of a screw driver or other tool to the adjusting screw 21 of the coating device.

90 As thus described and illustrated it will be apparent that the device is adapted to uniformly and evenly apply the adhesive to the tape, and the adhesive is prevented from drying before the coated tape is applied to the sheet or other object.

5 The cap and its hinged head may readily be removed from the receptacle for cleaning and filling the receptacle, and the hinged head may readily be turned back or swung to the open position of Figure 3 for threading the tape by hand through the device, as well as for the purpose of gaining access to the operating parts of the device for usual cleaning, adjusting or repairs.

10 It will be obvious that the coating device may be varied in size to adapt it for the purpose of coating various widths of paper strips or tapes, and while I have illustrated and described the invention as used for coating and affixing telegraphic records to telegram blanks, it will be understood that the device may be used for sealing the wrappers of packages &c.

20 Having thus fully described my invention, what I claim as new and desire to secure by Letters Patent is:—

25 1. The combination with a receptacle having a removable cap and an outlet slot in the cap, of a grooved head mounted on said cap, a pressure mechanism mounted in the grooved head, a tongue on the cap for co-action with the pressure mechanism, and means for varying the frictional contact between said pressure mechanism and the 30 tongue.

3. The combination with a receptacle and its slotted, removable cap, and a tongue on the cap, of a grooved head mounted on the cap, and adjustable pressure plate mounted 55 in the grooved head complementary to the tongue, and means for varying the frictional contact between said plate and tongue.

40 3. The combination with a receptacle and its cap having an outlet slot, and a tongue on the cap, of a complementary, grooved head mounted on the cap, pressure mechanism mounted in the grooved head, a serrated knife edge, forming the lower wall of the outlet slot, and means for adjusting the 45 pressure mechanism to vary the frictional contact between a tape and pressure mechanism at one side of the tape and between the tongue and knife edge at the other side of the tape.

50 4. The combination with a receptacle and its cap having a slot therein, of a recessed head hinged on the cap, co-acting means on the adjoining faces of the head and cap for guiding a tape across the slot, a channel 55 guide mounted on the top of the receptacle and cap for feeding the tape, and an affixing roller mounted on the head below the outlet of the tape from the cap and head.

5. The combination in a coating device 60 with a cap having an outlet slot, of a hinged head having a recess, and spaced oppositely extending hooks in said recess, a guide plate having end hooks snapped over the first mentioned hooks, a resilient pressure blade having contact with the guide plate, and an ad-

justing screw threaded in the head for co-action with said blade.

6. The combination in a coating and affixing device for a tape with a receptacle having a removable cap and an outlet slot therein, a head having a recess and hinged to the cap and providing a space for passage of a tape between the cap and head, a channel-guide mounted on the top of the device having a rounded guide-end above said space, a supporting arm mounted on the head and a pressure roller journaled in said arm, and guide fingers on said arm at the ends of the roller for guiding a tape, for the purpose described.

70 In testimony whereof I have affixed my signature.
